Primary Examiner — Deanna L Pratt(74) *Attorney, Agent, or Firm* — Eugene Vamos(57) **CLAIM**

The ornamental design for a galley box chair with table, as shown and described.

DESCRIPTION

FIG. 1 is a front perspective view of a galley box chair with table in a retracted position, showing my new design;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a back perspective view thereof;
FIG. 9 is a front bottom perspective view thereof;
FIG. 10 is a front perspective view of the galley box chair with table in an extended position and galley box door open;
FIG. 11 is a front elevation view thereof;
FIG. 12 is a back elevation view thereof;
FIG. 13 is a right side elevation view thereof;
FIG. 14 is a left side elevation view thereof;
FIG. 15 is a top plan view thereof;
FIG. 16 is a bottom plan view thereof;
FIG. 17 is a back perspective view thereof; and,
FIG. 18 is a front bottom perspective view thereof.
The broken lines are for environmental purposes only and form no part of the claimed design.
